(57) **CLAIM**

The ornamental design for a stackable wine tasting tray, as shown and described.

DESCRIPTION

FIG. 1 is a perspective view of a stackable wine tasting tray, showing my new design;

FIG. 2 is a top view of the stackable wine tasting tray of FIG. 1;

FIG. 3 is a bottom view of the stackable wine tasting tray of FIG. 1;

FIG. 4 is a front view of the stackable wine tasting tray of FIG. 1;

FIG. 5 is a back view of the stackable wine tasting tray of FIG. 1;

FIG. 6 is a left side view of the stackable wine tasting tray of FIG. 1;

FIG. 7 is another perspective view of the stackable wine tasting tray as shown in FIG. 1;

FIG. 8 is a cross-sectional front view of the stackable wine tasting tray as shown in FIG. 1;

FIG. 9 is another cross-sectional front view of the stackable wine tasting tray as shown in FIG. 1;

FIG. 10 is a front view showing two stackable wine tasting trays, as shown in FIG. 1, stacked on top of one another;

FIG. 11 is a perspective view of a stackable wine tasting tray, showing my new design;

FIG. 12 is a top view of the stackable wine tasting tray of FIG. 11;

FIG. 13 is a bottom view of the stackable wine tasting tray of FIG. 11;

FIG. 14 is a front view of the stackable wine tasting tray of FIG. 11;

FIG. 15 is a back view of the stackable wine tasting tray of FIG. 11;

FIG. 16 is a left side view of the stackable wine tasting tray of FIG. 11;

FIG. 17 is another perspective view of the stackable wine tasting tray as shown in FIG. 11;

FIG. 18 is a cross-sectional front view of the stackable wine tasting tray as shown in FIG. 11;

FIG. 19 is another cross-sectional front view of the stackable wine tasting tray as shown in FIG. 11; and,

FIG. 20 is a front view showing two stackable wine tasting trays, as shown in FIG. 11, stacked on top of one another. The right side views are identical to the left side views and are therefore omitted. The broken lines shown in FIGS. 1, 2, 7-9, 11, 12, and 17-19 form no part of the claimed design.

1 Claim, 20 Drawing Sheets
